UNITED STATES PATENT OFFICE.

EDWARD SAMUEL CHARLES BETTELEY, OF SURBITON, ENGLAND.

ELECTRICALLY-OPERATED INDICATING DEVICE.

Application filed January 21, 1927, Serial No. 162,643, and in Great Britain January 25, 1926.

This invention relates to electrically operated indicating devices, the chief object being to provide a simple and efficient constructional form of device of this character.

- 5 According to this invention there is provided an electrically operated indicating device comprising an electrically controlled element or elements pivoted intermediate the ends thereof and adapted to rotate an independently mounted disc or more than one disc or like member about the axis or axes thereof in either direction through the intervention of means on the said disc or discs, the arrangement being such that the angular movement of the disc or discs is greater than the angular movement of the pivoted element or elements. Other features are hereinafter set forth.

In order that the said invention may be clearly understood and readily carried into effect the same will now be described more fully, by way of example, with reference to the accompanying diagrammatic drawings, in which:

- 25 Figures 1 and 2 are elevations taken at right angles to one another of an indicating device embodying the invention,

Figure 3 is a section taken approximately on the line $\alpha-\alpha$, Figure 2, the operative electrical connections being also shown, and

Figure 4 is a similar view to Figure 3 but showing the indicating disc and relative operative parts in a different position.

Referring to the drawings, the indicating device, in the example shown, comprises a disc a adapted to move freely about the axis thereof passing through the centre of gravity of the disc, and provided with an unbalanced weight or element b which, as shown, projects laterally from the disc, the said disc being mounted by means of a spindle c associated therewith relatively to appropriate bearings afforded for instance in front and rear plates d , e , respectively.

40 The disc a is adapted to be moved angularly about its axis by means of a balanced member f pivoted centrally between the ends thereof, each end of the said member having associated therewith an armature g which may be in the form of a soft iron core. An electro-magnet h or the like is located at a

predetermined point below each armature and the axis of the disc is located so that the laterally projecting element b on the disc may be caused to rest under the action of 55 gravity on either of the said armatures, leaving one of the armatures at the maximum distance from its corresponding electro-magnet when the other armature is in engagement with its corresponding electro-magnet,

60 as shown in Figures 1, 3 and 4. Upon an electric current being passed under the control of a corresponding switch through the electro-magnet or the like having its corresponding armature spaced therefrom the

65 maximum distance, the said armature will be attracted, causing the other armature, upon which the said element b will then rest, to move suddenly upward and thereby give an impulse to the disc which is consequently

70 caused to revolve, and having absorbed the energy imparted to it by the armature, in a manner similar to a flywheel, continues to revolve, such as for example, from the position indicated in Figures 1 and 3 to the

75 position indicated in Figure 4, until the said element b has passed the maximum amplitude thereof when it is assisted by the action of gravity until coming to rest on the armature of the electro-magnet or the like through

80 which the current is passing. The said element may be constructed of soft iron or like substance so that it may be attracted by the said armature and damp out any tendency

85 of the disc to rebound when suddenly brought to rest. When current is passed under the control of a corresponding switch through the other electro-magnet or the like, the disc will be caused to revolve in an opposite direction, such as for example, from the

90 position indicated in Figure 4 to the position indicated in Figures 1 and 3, in a manner similar to that aforesaid. If desired, the disc a may be locked in either position by

95 means of a pivoted arm i adapted to be operated, against the action of a spring j , such as that shown, or the equivalent, by means

100 of an electro-magnet k or the like in series with the electro-magnets h or the like, the arm i , in the example shown, being adapted at one end thereof to engage with either of

two notches l on the periphery of the disc

and disposed at an angle of 90° with respect to each other, the other end of the said arm having an armature m adapted to be attracted by the electro-magnet k to permit the 5 disc to be rotated in the manner aforesaid.

It will be noted that the indicating symbol on the disc is in the form of an arrow which can be exposed when required through openings such as the segmental openings n in the 10 front plate d , but it will be understood that any other symbol or indicating means may be associated with the disc.

By providing a device such as above described, the following advantages can be obtained:—

1. The disc being free to revolve with respect to the axis thereof, the angular movement imparted to the disc by the armature can be made considerably larger than the angular movement of the armature itself.

2. The disc acting in a manner similar to a flywheel, absorbs the sudden impulse of the armature and so carries the unbalanced weight of the aforesaid element over the 25 maximum amplitude thereof.

3. The angular movement of the disc can be varied by the distance and position between the axis of the disc and the axis of the pivoted member or lever with which the armatures are associated.

4. The disc being free to revolve with respect to the axis thereof, the unbalanced weight of the said element will come to rest on one of the armatures, leaving the other armature at the maximum distance from the corresponding electro-magnet or the like, even though the indicator proper is moved in a vertical plane through a considerable angle in either direction.

40 5. The unbalanced weight in the form of the said element being constructed of soft iron or like substance, will be attracted by the armature of the electro-magnet or the like through which a current is flowing, and so damp out any tendency of the disc to rebound when suddenly brought to rest by striking the armature.

If desired, more than one indicating disc or the like and relative parts may be provided, in which event two or more discs and relative parts constructed and arranged substantially in the manner above described may, for example, serve as means for indicating the intended direction of movement 50 of a motor road or other vehicle, and also, if required, means for indicating that the vehicle is intending to stop.

55 What I claim is:—

1. An electrically operated indicating device comprising an indicating member mounted for free rotation, an electrically controlled element mounted for pivotal movement, electrically controlled means for operating the element, and means carried by the member to be engaged by the element in its

electrical operation to thereby impart to the member an angular movement in excess of the angular movement of the element.

2. An electrically operated indicating device comprising an indicator mounted for free pivotal movement, an operating element mounted for pivotal movement, electrical means for actuating the element, and means carried by the indicator to be directly engaged by that portion of the element on 70 one side of the pivot to impart a free movement to the indicator, the portion of the element on the opposite side of the pivot serving as a limit to such free movement.

3. An electrically operated indicating device comprising an indicator mounted for free pivotal movement, a balanced lever mounted adjacent the indicator, electromagnetic means for moving the lever on its pivot, and a projection on the indicator to be engaged by the lever when operated for moving the indicator through an angular length exceeding the angular length of movement of the lever.

4. An electrically operated indicating device comprising an indicator mounted for free pivotal movement, a balanced lever mounted adjacent the indicator, electromagnetic means for moving the lever on its pivot, a projection on the indicator to be engaged by the lever when operated for moving the indicator through an angular length exceeding the angular length of movement of the lever, means for normally holding the indicator in a predetermined position, and means for automatically releasing the holding means simultaneously with the movement of the lever.

5. An electrically operated indicating device comprising an indicator mounted for free pivotal movement, an operating lever mounted adjacent the indicator, independent electromagnets capable of selective energization and cooperating with the respective portions of the lever on opposite sides of the pivot to move the lever, and a projection on the indicator engaged by the lever in movement to impart free rotative movement to the indicator.

6. An electrically operated indicating device comprising an indicator mounted for free pivotal movement, an operating lever mounted adjacent the indicator, independent electromagnets capable of selective energization and cooperating with the respective portions of the lever on opposite sides of the pivot to move the lever, and a projection on the indicator engaged by the lever in movement to impart free rotative movement to the indicator, said projection serving to unbalance the indicator.

7. An electrically operated indicating device comprising an indicator mounted for free pivotal movement, an operating lever mounted adjacent the indicator, independ-

ent electromagnets capable of selective energization and cooperating with the respective portions of the lever on opposite sides of the pivot to move the lever, and a projection on the indicator engaged by the lever in movement to impart free rotative movement to the indicator, said projection being electric-

cally attracted by the energized electromagnets to prevent rebound movement of the indicator. ¹⁰

In testimony whereof I have hereunto signed my name.

EDWARD SAMUEL CHARLES BETTELEY.
